ELECTRONIC PLUG-IN MODULE FOR RADIA- TION ANALYZER OR THE LIKE

Stephens N. Sato, San Diego, Calif., assignor to Beckman
Instruments, Inc., Fullerton, Calif., a corporation of
California

Filed Sept. 7, 1965, Ser. No. 86,894

Term of patent 14 years

(Cl. D26—1)

FIGURE 1 is a front perspective view of an electronic plug-in module for radiation analyzer or the like embodying my new design;

FIGURE 2 is a right side elevational view of the module shown in FIGURE 1;

FIGURE 3 is a rear elevational view of the module shown in FIGURE 1; and

FIGURE 4 is a bottom plan view of the module shown in FIGURE 3.

I claim:

The ornamental design for an electronic plug-in module for radiation analyzer or the like, as shown.
